Primary Examiner—A. Hugo Word*Assistant Examiner*—Robin V. Taylor*Attorney, Agent, or Firm*—Fitzpatrick, Cella, Harper & Scinto[57] **CLAIM**

The ornamental design for a flashlight, as shown and described.

DESCRIPTION

FIG. 1 is a side elevational view of a flashlight showing my new design;

FIG. 2 is a top plan view thereof;

FIG. 3 is a front elevational view thereof;

FIG. 4 is a rear elevational view thereof;

FIG. 5 is a side elevational view of another embodiment thereof, the only difference being in the switch and proportion;

FIG. 6 is a perspective view of the embodiment of the flashlight shown in FIGS. 1-4 as seen from the top and one side;

FIG. 7 is a perspective view of the embodiment of the flashlight shown in FIG. 5 as seen from the top and one side; and,

FIG. 8 is a bottom plan view of the embodiment of the flashlight shown in FIG. 1.
